UNITED STATES PATENT OFFICE.

GEORGE E. BOMBERGER, OF INDIANAPOLIS, INDIANA, ASSIGNOR TO ANDERSON BOX COMPANY, OF INDIANAPOLIS, INDIANA, A CORPORATION OF INDIANA.

CHICK BOX.

REISSUED

Application filed February 17, 1928. Serial No. 254,933.

This invention relates to a ventilated chick box construction.

The chief object of this invention is to produce a chick box that is ventilated and which 5 will readily stack but which will not prevent air having access to a portion of the cover so that ventilation can be obtained therethrough when the boxes are in stacked relation.

10 The chief feature of the invention consists in the formation of the cover in stepped or offset relation so as to provide, when the boxes are stacked, a ventilating channel or space between adjacent boxes. The 15 box is also complementarily formed to accommodate, receive and support the stepped or offset cover.

15 A further feature of the invention consists in the reinforcing partitions provided for reinforcing the box and forming compartments therein.

20 The full nature of the invention will be understood from the accompanying drawings and the following description and 25 claims.

25 In the drawings Fig. 1 is a perspective view of two boxes arranged in stacked relation, illustrating an air passage formed therebetween. Fig. 2 is a perspective view of the 30 box with the cover removed.

30 In the drawings there is illustrated a shipping box of fibre board, or corrugated paper which embodies the invention and is suitable for shipping small live animals or birds 35 and is of the class commonly called chick boxes.

35 Heretofore to prevent smothering of the birds or animals within the box, spacing members in the form of strips were added 40 to the bottom or to the top or both of the box and thus, two adjacent boxes in stacked formation were provided with a passage or air space therebetween, by which air could enter the box through the several openings 45 provided in the cover. Heretofore, such separation has been obtained by gluing or nailing wooden strips about one inch square in cross section across either end of each cover. Such addition is expensive in that 50 there is the cost of the spacing strips, the cost of attaching same to the box and the postage cost, by reason of the increased weight. Also variations of the weight of the strips necessitate individual weighing of 55 each box to apply the proper postage.

The present invention eliminates this necessity. The box includes a bottom; a pair of side walls 11 and a pair of end walls 12, all being continuations of the bottom and formed from a blank by suitably cutting, scoring and 60 bending into the position as shown in Fig. 2. Each of the end walls 12 extends above and projects upwardly beyond the plane of the side walls 11 and the lateral extensions 13 of the end walls 12 lie parallel to the side 65 walls 11 and they are secured thereto as indicated at 15. The adjacent edges 15 of the adjacent pairs of lateral extensions 13 form a trough arrangement in the side wall 11. The end walls are apertured as at 16 and the 70 side walls at 17 for ventilation. To reinforce the box and form compartments therein, a pair of bracing partitions 18 and 19 are provided, each having a slotted matched connection at the center 20 and each including lateral extensions 21 for anchorage as at 122 to the adjacent side or end wall. The height of the partitions 18 and 19 is substantially that 75 of the side wall.

75 The cover is complementarily formed and 80 includes a main and intermediate body portion 22 apertured as at 23. Extending upwardly therefrom are the offset portions 24, connected to which, are the end portions 25 of said top. Depending at each end from the 85 top portions 25 are the end edges 26 and depending from the side portions of the top portions 25 are the portions 27, same being secured together as at 28, the partial side edge 27 including a lateral extension or flap 29 90 adapted to lie adjacent the end edge member 26. Median portion 22 of the top includes a side edge 30 which is extended as at 31 beyond said top portion towards the ends and the extension 31 is substantially equal in 95 length to the width of the offset 24 and the remainder of the stock constitutes the side edge portions 27, the parting being made at 28. The length of the extension 29 is substantially that of the width of the end edge 100 26 so that a substantially square blank can be utilized and after being cut and scored the parts are secured together in cover form as at 28 in the corners and as at 32 intermediate the ends which maintain said cover in the off- 105 set of channelled relation.

105 By reason of the foregoing construction the box and the cover can be formed from substantially rectangular blanks without any wastage and ventilating perforations can be 110

formed therein in a well known manner. When the boxes are arranged in stacked relation (see Fig. 1) a ventilating passage is provided between adjacent boxes, the air entering the boxes through the ventilating openings 23.

It will also be apparent that instead of elevating the ends and depressing the mid-portion of the box and cover the same might 10 be reversed subject, however, to the same condition found in the first form that the elevated portion include not less than half the total area of the box.

The invention claimed is:

15 1. A shipping box comprising a box bottom and a box top, said top including an offset portion and the bottom including a similar portion for registration therewith to form a ventilation passage when said box is 20 arranged in stacked relation with another box.

25 2. A shipping box top including an intermediate portion, a pair of offset portions secured thereto at opposite sides, a pair of end portions each secured to an offset portion and parallel to the intermediate portion, and 30 edge portions extending angularly of the end and intermediate portions and secured together in overlapping relationship adjacent the offset portions.

3. A shipping box top of the character defined by claim 2 characterized by the top being formed from a substantially quadrilateral blank without wastage, the remaining portion of the blank constituting edge 35 portions secured to the end portions of the top and providing extensions in the form of flaps for anchorage to the side edge portions to secure the same in top formation.

4. A shipping box including a bottom portion, a pair of sides secured thereto and extending transversely thereof, a pair of ends similarly arranged and terminating at a greater distance from the bottom than the sides, and flaps having the same depth as the 40 ends and constituting extensions thereof and arranged to lie parallel and be secured to the sides and project above the same, said flap terminations being in spaced relation for forming a notch in the completed side wall 45 50 of the box.

5. An article as defined by claim 4, characterized by the length of the flap being equal in length to the width of the side wall where- 55 by the blank is substantially quadrilateral and forms the box without wastage.

In witness whereof, I have hereunto affixed my signature.

GEORGE E. BOMBERGER.
